F. M. ASHLEY

FLEXIBLE SHADE FOR ELECTRIC LAMPS

Filed Nov. 8, 1920

INVENTOR

Frank M. Ashley

UNITED STATES PATENT OFFICE.

FRANK M. ASHLEY, OF NEW YORK, N. Y.

FLEXIBLE SHADE FOR ELECTRIC LAMPS.

Application filed November 8, 1920. Serial No. 422,489.

To all whom it may concern:

Be it known that I, FRANK M. ASHLEY, a citizen of the United States, and resident of the city of New York, in the county of Kings 5 and State of New York, have invented certain new and useful Improvements in Flexible Shades for Electric Lamps, of which the following is a specification.

My invention relates to shades for electric 10 lamps and the object of my invention is to provide a flexible translucent shade that can be easily attached to the bulb of an incandescent lamp and envelop the same.

The drawing is a fragmentary view of my 15 improved shade showing an electric bulb therein.

Referring to the drawing which forms a part of this specification, A indicates an incandescent electric light bulb and B an envelope of thin flexible rubber. C indicates a 20 ring of asbestos or other suitable material which is slipped over the small diameter of the bulb or may be made large enough to fit nearer to the larger end if desired, and fits 25 air-tight thereon. This ring C is provided with a circumferentially extending groove C' on which the reinforced band B' of the envelope B tightly fits. The circumference of the upper part of the opening of the ring C is 30 larger than the circumference of the lower part of the opening so to conform to the sloping sides of an electric bulb. D and D' are 35 check-valves of simple construction fixed on the envelope and through which air or other suitable gas is introduced to inflate the envelope B. A small tube with a conical end to fit the conically formed inlet D' may be 40 employed for this purpose, if desired. Artistic painting or advertising matter may be impressed or otherwise placed upon the envelope and displayed, if desired. Rubber such as used in the making of toy balloons may be used and has been found satisfactory 45 material from which to make the envelope or shade. The ring C prevents the heat generated in the bulb from injuring the rubber and this ring may be made considerably larger than shown in the drawing, if desired. When the envelope is fully inflated and the 50 lamp is operating the light shines through the shade. The less the envelope is inflated, the less light shines through and therefore the degree of brightness can be controlled to a

considerable degree by changing the thickness of the envelope as the same is relatively 55 deflated. When the envelope B is inflated the ring C will be subjected to a pulling stress which will cause the ring to more tightly grip the electric light bulb A.

Having thus described my invention, I 60 claim as new:

1. The combination of an electric incandescent lamp comprising a glass bulb, a ring mounted on the glass surface thereof in air-tight relation therewith, and an expandible 65 shade portion comprising a band which fits over said ring in air-tight relation therewith and is carried thereby.

2. A shade adapted to enclose a lamp bulb in air-tight relation, comprising an elastic 70 envelope having an opening with a reinforced elastic edge and a ring having its inner surface adapted to fit the surface of the bulb and having a groove, in which the edge of said opening fits.

3. A flexible shade adapted to enclose a lamp bulb in air-tight relation, comprising an elastic envelope having an opening with a reinforced elastic edge and a heat insulating ring having its inner surface adapted to fit 80 the surface of the bulb and having a groove, in which the edge of said opening fits, and a valve means through which said shade may be inflated.

4. A flexible shade comprising an envelope, 85 a lamp bulb, gas interposed between the envelope and the bulb, and a ring adapted to be pressed against the bulb by means of the gas in the envelope and means connecting the envelope and ring in air tight relation.

5. A flexible shade comprising an envelope supported by a bulb and having an opening in the envelope, gas being interposed between the envelope and bulb, a ring adapted to rest on the lower part of the bulb, the circumference of the opening in the upper part of the ring being greater than the circumference of the lower part thereof whereby the ring may be wedged on the bulb when the shade is inflated and means connecting the shade and 100 the ring.

Signed at New York city, in the county of and State of New York this 6th day of November A. D. 1920.

FRANK M. ASHLEY.
